US0D1107837S

(12) **United States Design Patent** (10) **Patent No.:** **US D1,107,837 S**
(45) **Date of Patent:** **** Dec. 30, 2025**

(54) **TEXTURED REPLACEABLE PICKLEBALL PADDLE SURFACE**

(71) Applicant: **Reload Technologies, Inc.**, Venice, CA (US)

(72) Inventors: **Nikola Vladimir Bicanic**, Venice, CA (US); **Troy Michael Hamner**, Carlsbad, CA (US)

(73) Assignee: **Reload Technologies, Inc.**, Venice, CA (US)

(**) Term: **15 Years**

(21) Appl. No.: **29/908,639**

(22) Filed: **Jan. 13, 2024**

Related U.S. Application Data

(63) Continuation of application No. 18/217,617, filed on Jul. 3, 2023, now Pat. No. 11,925,843, which is a continuation-in-part of application No. 18/110,386, filed on Feb. 16, 2023.
